ADJUSTABLE NOZZLE SUCTION CLEANERS

George A. Brace, Highland Park, Ill., assignor to The Hoover Company, North Canton, Ohio, a corporation of Ohio

Application December 12, 1950, Serial No. 200,421

3 Claims. (Cl. 15—361)

The present invention relates to suction cleaners and more particularly to a novel arrangement of the supporting wheels and the propelling handle whereby the nozzle is automatically elevated whenever the handle is in either of its normally non-propelling positions.

In cleaners employing rotary agitators, it is undesirable to leave an operating cleaner stationary on a carpet for an extended period. This is because the rapidly rotating agitator may change the appearance of the nap by imparting a sheen to it or, if left long enough, will actually wear away a part of the nap. This result is possible whether the handle is left at its inclined rest position or in its vertical storage position. The hazard is most likely to arise while the cleaner is converted to a dusting tool use; it is also frequently present during normal on-the-floor usage as when the user is suddenly called away to answer the door or telephone, or is moving furniture.

Previous attempts have been made to circumvent these hazards but these have proven unsatisfactory for failure to provide for all contingencies or because they require some initiating action on the part of the operator.

The present invention provides a simple arrangement which is automatically operable to elevate the agitator out of contact with a floor covering whenever the propelling handle is unsupported by the hand of the user. Stated conversely, the present invention operates to lower the agitator into a carpet handling position whenever the handle is moved from either of its two positions of rest to any cleaner propelling position.

Accordingly, it is an object of the invention to provide a new and improved suction cleaner.

Another object is the provision of new and simple automatic means for raising the agitator from the carpet whenever the propelling handle is in either of its two rest positions.

A further object is the provision of automatically operable means for lowering an agitator into contact with a carpet whenever the handle is moved from either of its rest positions into its cleaner propelling positions.

Still another object is the provision of a novel arrangement whereby the position of the operating handle determines the position of one or more of the cleaner supporting wheels with respect to the cleaner body.

A further object is the provision of a simple and effective nozzle range shifter in combination with an automatically operable agitator lifter.

Numerous other objects and advantages of the invention will become apparent from the following specification and drawings in which:

Figure 1 is a side view of a suction cleaner incorporating a preferred embodiment of the invention;

Figure 2 is a bottom view of the cleaner shown in Figure 1;

Figure 3 is a top view of the rear wheel carriage taken on line 3—3 of Figure 1;

Figure 4 is a vertical sectional view on line 4—4 of Figure 3;

2

Figure 5 is a vertical sectional view on line 5—5 of Figure 6 showing the converter in place; and

Figure 6 is a fragmentary rear view of the cleaner shown in Figure 5 with certain parts broken away.

5 Referring to Figures 1 to 6, it will be observed that the invention is shown incorporated in a suction cleaner of the type in which the axis of the motor-fan unit extends horizontally transversely of the cleaner body. The cleaner includes a main body casting 10 having a suction 10 nozzle 11 in communication with two upwardly and rearwardly extending housings 12 and 13. A generally cylindrical motor-fan unit 14 is pivotally supported between the upper ends of housings 12 and 13 in a manner which will be described in detail below. The forward end of 15 the main body 10 is supported by a pair of wheels 15, 15 concealed within skirts integral with the main casting. A pair of rear wheels 16 are journaled to a lever or carriage 17 pivotally connected to the main casting by a rod 18 and having a roller which rides along a trackway 20 carried by the motor-fan unit.

A rotary agitator 19 is detachably mounted within the nozzle and comprises a large diameter shell carrying a pair of rigid, helically arranged beater elements 20 and a pair of diametrically disposed bristle brushes 21.

25 Passageway 22 within housing 13 encloses the agitator drive belt 24, while passageway 23 within housing 12 constitutes a suction air passageway leading into the fan eye of motor-fan unit 14. The forward end of passageway 23 preferably expands so as to extend substantially the full 30 length of suction nozzle 11, as indicated by Figure 2.

The motor-fan unit 14 is journaled between the adjacent facing sides of housing members 12 and 13 in any suitable manner, such as illustrated in Figures 5 and 6. From these figures it will be noted that cylindrical motor shell 35 25 is closed by a removable plate 26 which also forms the outer wall of fan chamber 27 and encloses suction fan 28. Centrally disposed in plate 26 is fan inlet eye 29. Outwardly extending annular flanges on plate 26 cooperate with bearing and sealing rings 30 and with flanged ring 31 to support the motor-fan unit rotatably at the upper inwardly facing ends of housing members 12 and 13. Ring 31 is secured to the housing members by screws 32. The combined dust guard and finishing plate 33 is also held in place by screws 32.

40 A similar bearing and mounting structure is carried at the pulley end of the motor-fan unit and differs primarily in that there is no central opening in the plate corresponding to fan eye inlet 29.

An exhaust air conduit 34 is cast integrally with motor-fan unit 14 and its lower end communicates with the periphery of the fan chamber. A filter bag 35 is preferably provided with a bag ring 36 which is detachably secured to the end of passageway 34 by thumb nuts 37.

The propelling handle 38 is secured to a fitting 39 55 overlying conduit 34 and rigidly attached to the motor housing. Accordingly, it will be clear that the propelling handle, as well as the filter and exhaust air conduit, pivot with the motor-fan assembly.

As will be observed from the showing in Figures 1 to 6, the rear wheel carriage comprises a generally inverted cup shaped stamping 17. The forward end of the carriage is pivoted to the cleaner body at 18 while the rear end supports trunnions for rear wheels 16. The top surface of the carriage is slit at 40, 40 and the intervening portion 41 is depressed to form a slide channel for strip 42. Struck up tabs 43, 43 on strip 42 support a roller 44 at a slight angle to the horizontal.

70 Roller 44 bears against an arcuate trackway 45 secured to the underside of the motor-fan unit 14 at or near the longitudinal axis of the cleaner. The surface of the trackway is concentric to the axis of the motor-fan unit except for a pair of cammed roller receiving

recesses 46 and 47 and a lower limit stop 48. Recess 46 is located at the forward end of the trackway and in a position to receive roller 44 when the handle is in its storage position here shown as the vertical position, while recess 47 is located to receive the roller when the handle is in its desired inclined rest position. This position is preferably selected at a point just below the lower limit of the normal operating range. Both entrance corners of recess 47 and the rear entrance corner of recess 46 may be rounded slightly to facilitate the 10 egress of the roller when raising or lowering the handle from one of its two rest positions. A pair of torsion springs 9 about the rod 18 urge the carriage 17 upwardly to maintain the roller 43 in engagement with the trackway 45.

From the foregoing it will be clear that the arcuate portion of the trackway between the recesses represents the normal operating range of the cleaner handle while the arcuate portion between recess 47 and stop 48 constitutes the lower operating range of the handle when the cleaner is being used to clean beneath beds, tables and other low objects. Since all portions of the trackway within these two operating ranges of the handle are concentric with the axis of the motor-fan unit, it will be obvious that roller 44 riding there along will maintain the rear wheels in a uniform position with respect to the remainder of the cleaner and with respect to the front carrier wheels 15. However, should the operator place the handle in its storage position or merely release his grasp on the handle, roller 44 will fall either into recess 46 or recess 47 allowing the rear wheels to pivot upwardly about pivot 18 to the dotted line position indicated in the drawings. As a result, the suction seal with the nozzle lips is broken and the agitator is elevated well above the carpet nap. Accordingly, the cleaner motor can be left in operation indefinitely without the possibility of wear or injury to the carpet.

The cleaner may be converted to off-the-floor cleaning very quickly and simply. Converter port 49 is located in the side of the suction passageway directly opposite fan eye 29 and is normally closed by a snap-on cover 50.

The converter tool preferably comprises an L-shaped conduit 51 the shorter leg of which fits snugly within port 49 and extends into substantially airtight registry with fan eye 29. A key 52 on the outer side of the converter interfits with a notch 53 on the upper side of the converter port. A similar notch 54 on the lower side of port 49 receives a spring latch detent 55 to lock the converter in place. Latch 55 also cooperates with key 52 and notches 53, 54 to prevent rotation of the converter with respect to the cleaner body.

By reference to Figures 5 and 6 it will be noted that the converter tool interfits with a tab on the motor-fan unit to perform two important functions. Thus, the converter cannot be inserted until the motor-fan unit is in one of two positions and secondly, once the converter is in position the motor-fan unit cannot be rotated. These objectives may be served by providing a tab 56 on end plate 26 of the motor-fan unit which extends into similarly shaped notches 57 or 58 in the end of the converter tube 51. These notches are so positioned that if the handle is in the vertical position, tab 56 extends into notch 57. However, if the handle is in the inclined rest position when converting, tab 56 extends into notch 58.

From the foregoing it will be evident that the converter cannot be inserted and locked in place unless the handle is in its storage position or in its inclined rest position. In either of these positions, the rear wheels are elevated with the result that the nozzle and agitator are also elevated out of contact with the carpet. Once the converted is locked in place, the handle and the rear wheels are also locked insuring that the agitator will remain out of contact with the carpet so long as the converter remains in place.

The present invention also incorporates simple and 75

easily operated means for adjusting the nozzle to carpets of widely varying thickness without, however, interfering with the automatic nozzle raising feature described in detail above. The nozzle range shifting adjustment mechanism will be best understood by reference to Figures 3 and 4. From these figures it will be noted that roller 44 is quite long and that its axis is inclined to the horizontal. This roller is carried on strip 42 which is slidable crosswise of carriage 17. Normally strip 42 is held in a desired position by a control lever 60 pivoted to the underside of the carriage by a large diameter rivet 61. A compression spring 62 extends between the lower end of the rivet and the underside of lever 60 holding it snugly against the underside of the carriage. The notched forward end of lever 60 is received by the slotted end 63 of an extension on strip 42.

The upturned rear end 65 of lever 60 extends upwardly through an arcuate slot 66 in the carriage. Spaced apart, downturned tabs 67, 67 on the forward side of slot 66 provide a plurality of notches or steps for handle 65. Thus roller 44 can be shifted laterally to any desired position by depressing lever 65 against the action of spring 62 until the lever is below the lower end of the tabs and releasing it when it is opposite one of the notches. Spring 62 then presses the lever upwardly against the carriage locking the roller in the desired adjusted position.

Operation

30 The operation of the entire cleaner is thought quite obvious from the foregoing description but will be reviewed briefly. Let it be assumed that the range shifter control lever is in intermediate or normal position as illustrated in Figure 3 and that the propelling handle is in an inclined operating position as shown in Figure 1. Roller 44 then rides along the forward sector of track 45 between recesses 46 and 47. Rear wheels 16 and carriage 17 are held in definite relationship with the cleaner body to maintain the nozzle at a proper constant height for normal cleaning purposes.

35 If the operator should release his grasp on the handle, it will fall by gravity until roller 44 falls into recess 47 permitting carriage 17 and the rear wheels to pivot upwardly about pivot 18. When this occurs, the cleaner body pivots downwardly about the front carrier wheels 15 raising the nozzle, breaking the suction seal and elevating the agitator out of contact with the carpet. The cleaner may continue to operate for an indefinite period without any possibility of injury to the carpet. As soon 40 as the operator grasps the handle and either raises or lowers it slightly, roller 44 will pass out of recess 47 onto the elevated portion of the track causing the carriage and the rear wheels to be lowered and restoring the nozzle to its optimum operating position with respect to the carpet.

45 Should the operator take the cleaner onto a different type of carpet, let us say an extra thick carpet on which a higher nozzle operating height is desirable, the operator has but to shift the control lever 65 to adjust the nozzle. 50 This is accomplished simply by depressing lever 65 with the toe and shifting it to the right to the position marked "thick." Shifting of the lever moves the lower end of roller 44 into contact with track 45. As a result, carriage 17 pivots upwardly causing the cleaner body to rotate rearwardly about wheels 15 raising the nozzle mouth to the optimum height for the cleaning of thick carpets. Adjustment of the nozzle to thin carpets is accomplished in a similar manner by shifting the higher end of roller 44 into contact with track 45.

55 If the operator desires to clean beneath a bed or other low piece of furniture, he simply lowers the handle into the lower operating range. As he does so, the roller passes through recess 47 and onto the rearmost end of track 45. If the handle is raised to its vertical storage position, roller 44 rolls into recess 46 allowing the rear

wheels to pivot upwardly and resulting in the raising of the nozzle above the carpet.

If the operator desires to convert the cleaner to off-the-floor cleaning, it is merely necessary to remove converter cover 50 and insert converter tool 51 through port 49. This may be done when the handle is in either its storage position or its inclined position of rest and regardless of whether or not the motor is operating. In either handle position, the nozzle is elevated above the carpet and tab 56 on the motor-fan unit will align with either notch 57 or notch 58 in the end of the converter tool allowing it to be latched in position in registry with the fan eye. If, for any reason, the handle is not in the inclined rest position or the storage position, the converter tool cannot be inserted because tab 56 will abut the end of the converter and prevent it from being inserted far enough to be latched. However, once the converter is latched in position, tab 56 interlocks with one of the notches 57 or 58 on the converter to prevent the handle from being moved and thereby prevents the rear wheels from being lowered to bring the agitator into contact with the carpet.

While I have shown and described one embodiment of my invention, it is to be understood that it is to be taken as illustrative only and not in a limiting sense. I do not wish to be limited to the particular structures shown and described, but to include all equivalent variations thereof except as limited by the scope of the claims.

I claim:

1. A range shifting adjustment mechanism for the nozzle of a suction cleaner comprising a suction cleaner body having a suction nozzle, a propelling handle pivoted to said body having an arcuate sector, a motor-fan unit therefor, a pair of non-adjustable wheels for said cleaner, a vertically adjustable wheel carriage for said cleaner, means for adjusting said carriage vertically including a movable roller positioned between said carriage and said arcuate sector of said handle, said roller having a surface inclined slightly to the horizontal and having its axis extending crosswise of said sector, and a manually

10
15
20
25
30
35
40

operable lever for moving said roller axially to adjust said carriage vertically whereby said cleaner pivots about said non-adjustable wheels to adjust said suction nozzle to carpets of different thickness.

2. A range shifting adjustment mechanism as defined in the preceding claim in which said manually operable means comprises a lever extending rearwardly from said movable roller and having an end accessible for manual control at the rear of said cleaner, and means for supporting said lever for movement transversely of said cleaner.

3. In combination with a suction cleaner having a body provided with a suction nozzle, a rotary agitator therein, a motor-fan unit drivingly connected to said agitator, supporting wheels for said body including a pair of wheels vertically adjustable with respect to said body, a propelling handle pivoted to said body having two positions of rest, lever means pivoted to said body including means connecting one portion thereof to said adjustable wheels, roller means on said lever means and positioned to ride upon a cammed sector movable with said handle, said lever means and cammed sector arranged to move said adjustable wheels to raise said nozzle and agitator out of their carpet cleaning position when said handle moves into either of said rest positions and to lower said nozzle as said handle is moved out of said rest positions, and means supporting said roller at an angle to the horizontal and shiftable laterally with respect to said cammed sector to move said lever means vertically to adjust said nozzle to carpets of different thicknesses.
